UNITED STATES PATENT OFFICE.

LETHA B. SMITH, OF PORTLAND, OREGON.

SKIRT MARKER.

Application filed December 19, 1921. Serial No. 523,487.

To all whom it may concern:

Be it known that I, LETHA B. SMITH, a citizen of the United States of America, and resident of Portland, in the county of Multnomah, in the State of Oregon, have invented certain new and useful Improvements in Skirt Markers, of which the following is a specification, reference being had to the accompanying drawing.

10 My invention relates to devices for controllably directing by a current of air a stream of powdered chalk or the like, so as to produce a visible mark upon a skirt or other garment while depending from the 15 person of a wearer, in order to indicate thereon, preferably in a narrow, uniform, horizontal line, measurement, from above the level of a floor or base on which the wearer stands, of the length of the garment. 20 In devices of the general description aforesaid, a serious obstacle has been encountered in practice, namely, in respect to the use of a powder as a marking medium. It has been found hitherto impracticable to 25 effect discharge of the powder with certainty in that even uniformity of flow that is necessary to the successful operation of the apparatus. The same cause which interrupts the uniformity of flow of the powder, 30 to wit, the tendency of the powder to pack and choke the machine, tends to cut off the discharge altogether.

By my invention not only is an exceedingly simple, economical, and effective apparatus produced, but also provision is made therein for insuring uniformity of powder discharge therefrom, and for eliminating the choking of the machine while in use by packing or congestion of the powder 40 at any point along its line of travel.

Moreover, by my invention provision is made for facilitating the cleaning of the powder-discharge conduit, and for freeing it of any particles of dust that might possibly stick therein after a period of disuse.

What constitutes my invention will be hereinafter specified in detail and succinctly set forth in the appended claims.

In the accompanying drawing,

50 Figure I is a side elevation of my invention complete in present preferred form of embodiment, a portion of the air supply tube being broken away in order to accommodate the illustration to the size of the sheet.

Figure II is a top plan view of the subject matter of Figure I with the air supply bulb omitted.

Referring to the numerals on the drawing, 1 indicates a pedestal of any suitable weight, material, and dimensions, and 2 an upright rod or standard supported thereby. The pedestal may be placed in any convenient position desired upon a floor or other supporting base upon which a person may stand while my marker is being employed in use. The standard 2 is preferably provided with graduation marks indicative of variations in elevation above the level of the bottom of the pedestal.

Secured with longitudinal adjustability to the standard, is a downwardly opening receptacle cover 3, provided preferably with a depending annular flange 4. The cover 3 is, for the purpose of adjustable connection with the standard, preferably provided with a loop 5 whose opposed sides are apertured for the sliding accommodation within them of the standard. An abutment screw 6, working to and from the standard 2 in a threaded aperture fitted to it in the back 7 of the loop 5, affords a simple and convenient means of adjustably fastening to the standard the loop and the cover 3 which it carries.

Fitting snugly but separably within the flange 4 is the open end of a receptacle or bowl 9. Means for uniting the bowl 9 to the cover 3 in an air-tight joint are provided, consisting preferably of stud pins 10 projecting from the outside of the bowl in diametrically opposite directions, and taking into corresponding inclined slots 11 in the flange 4. The function of said slots is, in effect, that of a screw thread adapted to force the upper edge of the bowl into close contact with the under side of the cover 3, and to hold it there.

Communicating with the interior of the upper part of the bowl 9, is a discharge 100 mouthpiece 12, having a thin, flat, horizontal opening as indicated by dotted lines in Figure I. The mouthpiece 12 is preferably located diametrically opposite the loop 5.

At a point, preferably between said 105 mouthpiece and loop and beyond the center of the cover 3, is located a nipple 15 carried by said cover, and to it is fastened one end of a flexible or rubber tube 16, whose other end is in operative communication with a 110

source of compressed air supply, preferably a simple valve-controlled rubber bulb 17 of the kind ordinarily used in atomizers for generating air currents.

5 The operation of my apparatus may be described as follows: Preparatory to use, the bowl 9 is supplied with a modicum of marking medium in the form of a pulverulent powder. Enough may be used at one 10 time, depending, of course, on the capacity of the bowl, to mark a number of garments, but the quantity of powder used for a charge must be restricted so as to leave ample air space within the bowl below the cover 3. 15 After the bowl is properly charged and fastened to the cover 3, discharge of the powder through the mouthpiece 12 is effected by pressure between the thumb and finger of the bulb 17. Such pressure 20 communicates a jet or puff of air through the nipple 15 into the interior of the bowl against the pulverulent mass of powder in the bottom thereof with the effect of lifting a portion thereof into the air space in the 25 bowl above it thereby loading the atmosphere of the bowl with powder in suspension only. By the same operation compression of the air confined by the cover within the bowl is effected, and the powder-laden 30 air seeks exit through the mouthpiece and upon discharge therefrom performs the marking function required of it.

It may be observed that the disposition 35 of the mouthpiece 12 and nipple 15 relatively to the cover 3 facilitates the operation described by tending to insure discharge of the contents of the bowl in pulverous form. Repeated ejections of air or puffs from the 40 bulb will suffice in time to exhaust the contents of the bowl 9, which may be conveniently removed, replenished and restored to place as often as need be.

The only part of the apparatus that may 45 ever need cleaning for operative purposes, is the interior of the mouthpiece 12 which is at all times open to direct easy access.

It is obvious that the tube 16 may be 50 made of any length desired, and that thereby the operation of the bulb 17 may be brought under control of a person wearing a garment or of an attendant for the marking by either the one or the other, as preferred.

What I claim is:

1. In a device of the kind described, the 55 combination with a closed receptacle having a discharge mouthpiece, of means for load-

ing the atmosphere within the receptacle with powder in suspension only, and for ejecting said powder-laden atmosphere through the mouthpiece. 60

2. The combination with a standard, and its support, of a closed receptacle adjustable vertically upon the standard, a discharge mouthpiece for the receptacle disposed above the bottom of the receptacle, and means for forcibly directing a current of outside air into the interior and against the bottom of the receptacle and thence outwardly through said mouthpiece in one 70 operation.

3. The combination with a standard, and its support, of a receptacle top vertically adjustable upon the standard, a means of forcible air discharge through said top, a bowl suspended below said top in closed 75 connection therewith, and a discharge mouthpiece carried by said bowl and operatively disposed above the bottom thereof.

4. The combination with a standard, and its support, of a receptacle top vertically adjustable upon the standard, a depending annular flange upon said top, a bowl fitting said flange and provided with a discharge mouthpiece disposed above the bottom thereof, means of forcible air discharge into the 80 bowl against the bottom thereof, and complementary members on the bowl and top for uniting the bowl to the top with relative compression effect of one against the other. 85

5. The combination with a standard, and its support, of a receptacle top vertically adjustable upon the standard, a depending annular flange upon said top, a bowl fitting said flange and provided with a discharge 90 mouthpiece disposed above the bottom thereof, means of forcible air discharge into the bowl against the bottom thereof, and complementary members on the bowl and top for uniting the bowl to the top with relative compression effect of one against the other, 95 said complementary members consisting of inclined slots and stud pins adapted operatively to engage the same. 100

In testimony whereof, I have hereunto set my hand in the presence of two subscribing witnesses.

LETHA B. SMITH.
